UNITED STATES PATENT OFFICE

149,517

DESIGN FOR A GARMENT HANGER

Julia Read, New York, N. Y.

Application January 25, 1947, Serial No. 136,424

Term of patent 14 years

(Cl. D80—8)

To all whom it may concern:

Be it known that I, Julia Read, a citizen of the United States of America, residing in New York city, county of New York, and State of New York, have invented a new, original, and ornamental Design for a Garment Hanger, of which the following is a specification, reference being had to the accompanying drawing, forming part thereof, wherein,

The rear of the garment hanger is identical in appearance with the front shown.

I claim:

The ornamental design for a garment hanger, substantially as shown and described.

JULIA READ.
